UNITED STATES PATENT OFFICE.

FRANK W. DREW, OF MINNEAPOLIS, MINNESOTA.

VOUCHER SHEET.

1,411,847.

Specification of Letters Patent.

Patented Apr. 4, 1922.

Application filed September 24, 1920. Serial No. 412,430.

To all whom it may concern:

Be it known that I, FRANK W. DREW, citizen of the United States, resident of Minneapolis, in the county of Hennepin and

5 State of Minnesota, have invented certain new and useful Improvements in Voucher Sheets, of which the following is a specification.

This invention relates to voucher sheets adapted for use in connection with the main- 10 tenance of a record providing a plurality of time divisions which are adapted to receive labor charge entries therein, and for use as a negotiable instrument to be filled out in payment of labor charges which instrument 15 is adapted to be endorsed by the payee whereby a receipt is had. These novel voucher sheets are useful, not only in pro- viding means for the daily entries of nota- tions of time-units of labor, usually hours or 20 fractions thereof, but also for the daily entries of such hours of labor under variant classifications. The necessity for such diversified classification arises from the fact 25 that the different rates of payment are necessary for the same time-unit for the same labor and the same individual. For example, such classification is here shown as straight time, over-time pro rata, over-time rate and a half, and over-time double rate.

30 These novel voucher sheets are adapted to be used in complementary pairs and when so used it is preferable that each sheet of such pair be either loosely or permanently bound in a suitable holder. For such use provision 35 is made for the separation of one sheet of the complementary pairs. Such separable or detachable sheet is that which may be given to the payee whose labor charges are noted on the sheets. Obviously, when these

40 voucher sheets are used in complementary pairs the same identical notations are made in the corresponding spaces provided for such notation on each sheet. This may be done by entering the proper notations twice

45 but, in practice, is effected by means of the usual sheet of carbon paper which is inserted between the complementary pairs when notation is made upon either one. When referring to these voucher sheets as used in complementary pairs, one of the sheets may con-

50 veniently be referred to as the record sheet and the other may be referred to as the detachable or separable sheet. These two terms are employed only for the purposes of

explanation as of course it is understood that 55 the series of pairs of sheets may all be held together in an ordinary form of loose-leaf binder.

The object of this invention is to provide a new and improved voucher sheet. 60

Other objects of the invention will more fully appear from the following description and the accompanying drawings, and will be pointed out in the annexed claims.

In the drawings there has been disclosed a 65 selected embodiment of this invention as particularly adapted for use in railroad accounting, but it is to be understood that the invention is not confined to the exact features shown as various changes may be made 70 within the scope of the claims which follow.

In the drawings:

Figure 1 shows voucher sheets in comple- 75 mentary pairs in the manner in which they may be conveniently bound in a holder.

Figure 2 is a plan view of the obverse face of two duplicate voucher sheets.

Figure 3 is a plan view of the reverse face of the same.

In the embodiment here shown the 80 voucher sheets are disclosed in joined duplicates as such is the form in which this invention is now being employed in railroad work. Each voucher sheet has an obverse face 4 (Figure 2) provided with divisions 85 within which the labor charge entries may be noted. The reverse face 5 (Figure 3) of each voucher sheet is the one which provides the negotiable instrument having spaces to be filled out in payment of the labor charges 90 noted on the obverse face of the voucher.

The obverse face 4 is provided with a longitudinally extending upper portion 6 which is provided as shown with spaces within which entries may be made to identify the 95 employee and the year and month within which the labor was performed. The middle portion of this obverse face has a plurality of vertical or transverse lines which provide this portion with a plurality of columns. These columns are consecutively numbered to indicate the successive days of the month. As shown in the drawings the latter half of the month is so indicated.

Owing to the necessity for different rate 105 classifications for the same labor of the same employee, it is necessary that each daily column be provided with a plurality of sub-

divisions within which the time-units of labor performed within any given day may be appropriately entered. This subdivision is effected by means of a plurality of horizontal or longitudinal lines which thus provide the defined spaces or sub-divisions 8 to receive entries under the appropriate classifications.

This obverse face 4 is also provided with 10 a column 9 having sub-divisions wherein may be entered the total time for the period covered by the voucher sheet for labor performed in the different classifications. Another vertical column 10 is similarly provided so that the different money rates per 15 unit of labor may be placed opposite the different classifications, and preferably, beyond these total time and rate columns is placed the "amount column" so that the total sum due the given employee for each of the 20 different rate classifications of labor performed may be entered in this amount column. The horizontal or longitudinal lines also provide a "total" row 12 wherein the 25 total time of labor for each day and the total amount for the labor for the period covered may be entered in the appropriate columns which this "total" row intersects.

The obverse face of this voucher sheet also 30 contains a blank lined portion wherein defined spaces 13 are provided for notation of the amount and identification of any deductions which are charged against the employee for the period of the sheet. A subdivision 35 14 is also provided in the "amount" column 11 wherein may be entered the sum of the deductions, opposite the heading "Less deductions." The difference between said "total" amount and the deductions provides 40 the balance due the employee. Such charge is noted in the space 15, as shown in Figure 2, and constitutes the notation of the total money equivalent of said entries of labor performed by the employee or payee.

45 The obverse face also preferably has a portion provided with a space 16 to receive the endorsement of the employee to whom payment is made for the labor performed. This space is provided so that the negotiable instrument provided on the reverse face of this voucher may be cashed by the employee after being filled out by the payer. This endorsement constitutes a receipt not only for the money had but also as an acknowledgment of payment for labor performed as set forth by the entries on the obverse face of the sheet.

The reverse face 5 of the voucher sheet provides the negotiable instrument or pay 60 check of the payer for the total money equivalent of the performed labor. This pay check is provided with spaces 17 to be filled out, in the selected embodiment here shown, by the payer company. The data 65 to be entered in the various spaces is defi-

nately and clearly indicated in the accompanying drawings and enumeration would be simply repetitious.

These voucher sheets are preferably employed in complementary pairs. A convenient number of such complementary pairs are preferably bound together in a looseleaf or permanent binder. As here shown, in Figure 1, they are shown as permanently bound in a holder 18. When used in complementary pairs, one sheet of each pair is adapted to remain in the holder and constitutes what may be termed the record sheet 19. The other sheet of a complementary pair is termed the separable sheet 20. The separable sheet is provided with a line of separation 21, the usual perforated line to facilitate removal of the sheet from the portion 22 retained by the binder or holder 18. When assembled in bound form, as indicated in Figure 1, the separable end record sheets alternate so that identical notation may be made on each of a complementary pair as by use of carbon paper as is common.

In practical use, the reverse face of the record sheet 19 may be left blank to save printing costs as the negotiable instrument spaces need not necessarily be filled out by the time-keeper. As shown in Figure 1, the separable sheet 20 is above its complementary record sheet 19 so that the carbon imprint is received on the record sheet. Such arrangement is obviously optional as the arrangement may be reversed and the record sheet placed on top of its separable sheet in which case original entry will be made on the record sheet and the carbon imprint or corresponding entry will be received on the separable sheet.

As here shown, these novel voucher sheets are preferably prepared in joined duplicates. That is, the voucher sheets are prepared in duplicate on a single piece of paper, being readily detachable by tearing or cutting along the perforated line 23. This procedure is simply a matter of convenience as each retained or record page of the holder will contain two record sheets as shown in Figure 1. The duplicate record sheets on a single page are not provided with a perforated line of separation, simply a longitudinally extending blank portion 24 there appearing.

Having thus described my invention, what I claim as new and desire to secure by Letters Patent is:

1. A voucher sheet having on its obverse face an appropriately designated space for endorsement and a plurality of appropriately designated time divisions, each of the divisions having a plurality of appropriately designated sub-divisions whereby different labor time-unit entries may be made in each division; and an appropriately designated space to receive notation of the total

money equivalent of said entries; and having on its reverse face a negotiable instrument with appropriately designated spaces to be filled out in payment of said total 5 money equivalent whereby, upon endorsement a receipt is thereby had.

2. A voucher sheet having on its obverse face a heading space appropriately designated to indicate the payee, a "straight time" 10 space, an "overtime" space, said time spaces divided into a plurality of "day" spaces followed by "total time," "rate" and "amount" columns, the "amount" column 15 extending below the time spaces and being intercepted by a "less deduction" space and a "balance due" space, itemized "deductions" spaces underlying the time spaces and opposite the "less deduction" and "balance due" spaces, and a transversely arranged 20 endorsement space in advance of the time and heading spaces; and having on its reverse face a negotiable instrument with appropriately designated spaces to be filled out in payment of the total money equiva-

lent noted in the "balance due" space where- 25 by, upon endorsement, a receipt is thereby had.

3. A plurality of complementary pairs of voucher sheets, a holder to retain the sheets together, each pair comprising a record 30 sheet and a separable sheet, each sheet having on its obverse face a plurality of appropriately designated time divisions to receive notations of a plurality of labor charges, whereby each complementary pair 35 is adapted to receive the same charge notations, each separable sheet having a line of separation adjacent the retaining means whereby the major portion of the separable sheets may be removed from the holder, each 40 separable sheet also having on its reverse face a negotiable instrument with spaces to be filled out for payment of said labor charges.

In witness whereof, I have hereunto set 45 my hand this 18th day of September, 1920.

FRANK W. DREW.
